MANUFACTURING COMPANY, A CORPORATION OF NEW JERSEY.

EMBROIDERING ATTACHMENT.

1,147,457.

Specification of Letters Patent. Patented July 20, 1915.

Application filed November 26, 1913. Serial No. 803,115.

To all whom it may concern:

Be it known that I, CHARLES STAFFORD, a citizen of the United States, residing at Elizabeth, in the county of Union and State 5 of New Jersey, have invented certain new and useful Improvements in Embroidering Attachments, of which the following is a specification, reference being had therein to the accompanying drawings.

10 This invention has for its object to provide an embroidery-thread looper which shall be effective in operation and easily and cheaply constructed.

Heretofore, as employed in embroidering 15 attachments of the type represented in the United States Patent to G. W. Baker, No. 297,100, of April 22, 1884, the oscillatory and endwise-movable looper has been constructed with a shank forked at its operative 20 end to form two eccentrically disposed thread-fingers integral therewith of which one has a thread-aperture adjacent the outer end and a second aperture at its opposite end leading at an inclination with the looper- 25 shank to a point at the base of the fork intermediate said fingers, and the looper has required to be otherwise shaped at the base of said fork for proper handling of the needle-thread by which the loops of embroidery 30 thread were stitched upon the face of the fabric.

According to the present improvement in its preferred form, the looper is formed of a straight pin reduced and flattened near 35 one end to form a shouldered boss beyond which it is further reduced to form an axial thread-finger. Upon this flattened boss is fitted and secured by riveting the correspondingly apertured end portion of a bent 40 sheet-metal plate in the form of a punching having adjacent the opposite end and intermediate the ends additional apertures to receive and guide the embroidery thread. This plate has its thread-apertured outer 45 portion bent into substantial parallelism with the unapertured finger from which it is sufficiently spaced to freely admit the needle of the stitching mechanism and to provide sufficient lengths of embroidery thread 50 to produce coils or loops of the requisite size for attachment to the fabric by the fastening stitches. The bend in the apertured plate is of such curvature and arrangement that after lateral deflection of the stitching 55 thread leading from the fabric to the nee-

dle by the oscillation of the eyed finger thus formed the subsequent feeding of the work changes the lead of the stitching thread from the fabric in such manner that it slips around such bend, thus serving as a needle-thread cast-off, and assumes a position back of the needle-point so as to insure the proper laying of the stitches.

In the accompanying drawings, Figure 1 is a side elevation and Fig. 2 a front end 65 elevation of an embroidery attachment constructed in accordance with the present improvement, with the needle-bar and presser-bar of a sewing machine to which it is attached. Figs. 3, 4 and 5 are perspective 70 views representing in different stages of operation the coöperation of the needle with the embroidery-thread looper. Figs. 6 and 7 are perspective views showing respectively the shank portion of the looper having the 75 integral axial thread-finger and the eyed finger detached therefrom. Fig. 8 is a detail view of the apertured sheet-metal plate from which the eyed finger is formed.

The frame of the attachment comprises 80 the plate 1 having means for fastening it to the presser-bar and provided with the depending presser-foot shank 2 and foot-plate 3 and with the standard 4 carrying the stud 5. Fulcrumed upon the stud 5 is the swinging 85 lever 6 carrying the lateral stud-pin 7 intermediate its ends and provided at its lower end with the forked extremity 8. Also fulcrumed upon the stud 5 is the swinging 90 lever 9 provided near its lower end with the lateral pin 10 and having depending from a lateral extension thereof the bent fork 11.

Journaled upon the fulcrum-stud 12 sustained by an extension of the standard 4 is the angular operating lever provided with a 95 lateral arm 13 formed with the fork 14 embracing the needle-clamp stud 15 upon the lower extremity of the sewing machine needle-bar 16 and provided intermediate its ends with an enlargement containing the 100 transverse cam-slot 17 embracing the stud-pin 7 of the lever 6. The operating lever has a depending arm 18 provided with a fork 19 loosely embracing the pin 10 of the lever 9. In the reciprocation of the needle-bar the levers 6 and 9 are given differential 105 swinging movements. The lateral member 20 of the frame is formed with an apertured bearing lug 21 in which is journaled the reduced rearward portion 22 of the looper 110

rock-shaft formed with the flattened and spirally twisted middle portion 23 embraced by the fork 11 of the lever 9 and provided at its forward extremity with the cylindrical 5 socket portion 24 having an annular groove entered by the fork 8 of the lever 6. Secured within the socket of the part 24 by means of the set-screw 25 is the cylindrical shank 26 of the looper which is journaled within an 10 aperture in the presser-foot shank 2.

The looper is in the form of a straight pin reduced near its forward end to form the shouldered and flattened boss 27 and is further reduced beyond the same to form the 15 embroidery-thread spreading finger 28 which is shown slightly tapered and provided with a rounded extremity to facilitate retraction from the embroidery-thread loops. The laterally offset or eccentric eyed embroidery- 20 thread carrying finger 29 is in the form of a flat plate with its shank portion 30 bent at substantially a right angle with the operative portion and provided with an elongated aperture 31 fitted upon the flattened boss 27 25 to which this finger is preferably secured by riveting over the end of such boss. The finger 29 is formed with the transverse thread-eyes 32 and 33 disposed respectively at its outer end and adjacent the bend at the 30 heel thereof.

The eyed or thread-carrying looper-finger is preferably formed of a sheet-metal punching with the round and elongated apertures at the ends and the round aperture intermediate the ends produced by punching, as 35 represented in Fig. 8; while the reduced axial portions of the pin 26 may be turned in a manner well known and the part 27 subsequently flattened in case it is desired to 40 provide positive locking means to prevent the shifting of the eyed thread-finger around the non-apertured thread-finger. The thread-fingers of the looper are spaced apart to freely admit the sewing needle 34 between 45 them in the stitching operation and to dis- tend the embroidery-thread between them to form loops or coils of the requisite size for the ornamental seam, and the bend in the plate 29 30 is of such curvature and arrangement as to constitute this intermediate part 50 of the looper element a needle-thread cast-off, as will later appear.

In threading the attachment for operation the embroidery thread *e* is led from the 55 source of supply through the aperture 35 of an ear 36 of the plate 37 secured upon the arm 13 of the operating lever, thence upwardly through the thread-eye 38 sustained by the fulcrum-stud 5 and downwardly 60 through the eye 39 of a second ear 40 of the plate 37 between the latter and the free end of a U-shaped nipper-spring 41 having an apertured flange entered and clamped in position by the screw-stud 12. From the eye 65 39 the thread is led through an aperture 42

in the lateral lug 43 of the presser-foot shank to the inner face of the thread-finger 29 and through the eye 33 at the heel and finally through the delivery eye 32 at the extremity of the thread-finger from which it 70 is led to the face of the work.

In the operation of the device, upon the rise of the needle at the completion of a stitch, the looper advances and projects the axial finger 28 beyond and to one side of 75 the needle-thread *t*, with the eyed and eccentrically arranged thread-finger 29 at the farther side from the stitching thread, as represented in Fig. 3. At the completion of an advance movement of the looper it receives 80 a semi-rotation which throws the eyed thread-finger over against the needle-thread to deflect the same laterally from the needle-path and at the same time bends the portion of embroidery-thread between the 85 delivery eye of such finger and the work over the axial finger 28 to form an embroidery thread-loop, as represented in Fig. 4. The subsequent feed of the work longitudinally of the looper brings that limb of the embroidery-loop attached to the work rearward of the needle-point while the other limb is in front of the same, as represented in Fig. 5; and at the same time the lead of 90 the needle-thread to the work is so shifted 95 endwise of the looper-shank that its middle portion is caused to slip backwardly on the curved cast-off portion of the eyed thread-finger so as to position it rearward of the point of the needle to insure against the 100 descent of the needle in a loop of its own thread. As the point of the needle descends below the upper limb of the embroidery-thread loop the looper recedes to initial retracted position and leaves the embroidery- 105 thread loop around it to be bound upon the face of the fabric *m* by the strand of needle-thread then extending from the needle-eye to the work. As will be observed by reference to Figs. 3, 4 and 5, the advance 110 of the looper is timed to occur just as the point of the rising needle leaves the work, the cross-over movement of the eyed thread-finger occurring while the needle is still rising, and the descent of the needle for a 115 new stitch occurring just after the embroidery-thread loop has been distended by the feeding movement to embrace the needle-path, as indicated by the arrows in the several figures.

Heretofore, with the integral construction of the looper with its two eccentrically disposed thread-fingers, great care has been required in shaping the different parts to properly handle the embroidery and stitching threads and in drilling the inclined aperture at the heel of the eyed thread-finger, involving hand work to such extent as to bring the cost of the looper to exceed the combined cost of all other parts 120 125 130

of the attachment. By the present improvement, as above described, wire of the requisite size may be selected for the looper-shank and automatically turned in a monitor lathe to form the axial thread-finger and adjacent boss to receive the additional looper member; the latter being cut out by punching from sheet-metal in the form represented in Fig. 8, and subsequently shaped by means of suitable dies in readiness for riveting upon the boss of the shank member, thereby almost wholly dispensing with hand work and insuring absolute uniformity in both the dimensions and shapes of the component parts, and reducing the cost of the looper to a small fraction of that of the older form of looper.

While the axial thread-finger integral with the cylindrical looper-shank is an important feature of the improvement by means of which this portion of the looper may be automatically turned into the proper form, a still more important part of the present construction is the employment of a separate sheet-metal plate, capable of being shaped merely by the use of suitable dies, so that no drilling, filing or polishing is required in order to provide the necessary thread-eyes and the proper needle-thread cast-off at the heel or base of the eyed thread-finger.

Having thus set forth the nature of the invention, what I claim herein is:—

1. A looper for embroidering attachments comprising a pin reduced at one end to form an axial thread-finger and an adjacent

shoulder, and an angular plate apertured and secured upon the reduced portion of said pin adjacent said shoulder and having an operative portion arranged at the side of and spaced from said thread-finger and eyed to receive an embroidery thread.

2. A looper for embroidering attachments comprising a pin reduced at one end to form an angular boss and an axial thread-finger extending therefrom, and an angular plate apertured to fit and secured upon said boss and provided with a portion arranged at the side of and spaced from said thread-finger and eyed to receive an embroidery thread.

3. A looper for embroidering attachments comprising a pin reduced at one end to form an axial thread-finger and an adjacent shoulder, and an angular plate apertured and secured upon the reduced portion of said pin adjacent said shoulder and having an operative portion arranged at the side of and spaced from said thread-finger and eyed to receive an embroidery thread, said plate being bent intermediate its angularly disposed portions to form an external needle-thread cast-off surface at the heel of the eyed portion.

In testimony whereof, I have signed my name to this specification, in the presence of two subscribing witnesses.

CHARLES STAFFORD.
